[57] CLAIM

The ornamental design for a frame for the leading edge
of a glider, as shown.

DESCRIPTION

FIG. 1 is a perspective view of a frame for the leading
edge of a glider showing my new design;

FIG. 2 is a right-side elevational view of FIG. 1;

FIG. 3 is a left-side elevational view of FIG. 1;

FIG. 4 is a top plan view;

FIG. 5 is a front elevational view;

FIG. 6 is a bottom plan view; and

FIG. 7 is a rear elevational view.

FIG. 1

FIG. 2

FIG. 3

FIG. 4

FIG. 5

FIG. 6

FIG. 7
